UNITED STATES PATENT OFFICE.

STEPHEN C. LONERGAN, OF PAWTUCKET, RHODE ISLAND, ASSIGNEE TO SAYLES FINISHING PLANTS, INC., OF SAYLESVILLE, RHODE ISLAND, A CORPORATION OF RHODE ISLAND.

LABEL FOR WOUND OR ROLLED FABRICS.

Application filed January 27, 1922. Serial No. 532,098.

To all whom it may concern:

Be it known that I, STEPHEN C. LONERGAN, a citizen of the United States, residing at Pawtucket, county of Providence, and State of Rhode Island, have invented an Improvement in Labels for Wound or Rolled Fabrics, of which the following description, in connection with the accompanying drawings, is a specification, like characters on the drawings representing like parts.

This invention relates to new and useful improvements in labels, and more particularly to labels for cloth or other fabric wound or supported upon a holder.

When cloths and other fabrics are finally prepared for shipment or are to be placed upon the market, they are frequently wound upon a holder, or as it is commonly termed, a "board." The board or holder may be of any character or form adapted to support the cloth or fabric, but usually it is as its name implies, a flat, board-like structure, either made of a single piece of material or built up from constituent parts, so that when the cloth or fabric is wound thereon, the ends of the holder or board appear at the end of the cloth or fabric roll.

For shipment, packing, and other purposes, it is desirable that the holders or boards on which the cloth or fabric is wound, occupy as little space as consistent with the necessary dimension to secure strength and stability, and as a consequence, such holders are usually made only sufficiently thick to answer the above requirements. On the other hand, the exposed ends of such thin holders offer little opportunity for attachment of labels or other printed matter, so that some dealers or manufacturers have sought to improve the appearance of the goods by winding them on a heavier and more expensive holder or board, or even a reel, the end portions of which offer the desired dimension for receiving a label or other advertising matter. Such heavier board, reels and the like, however, add materially to the cost and occupy large space when the rolled or wound fabric is to be packed or shipped, so that an important feature of the present invention consists of a label adapted for use in connection with the less expensive and thin holders or boards and yet has an information-bearing portion of large dimension covering the end of the

board, and in part overlying a portion of 55 the built-up roll of fabric.

It is not usually convenient to attach the label to the goods until after they are wound upon the holder, and a further feature of the present invention is a label 60 formed preferably of flexible sheet material bent to provide two legs, both adapted to be inserted between the same surface of the holder and the adjacent cloth or fabric wound thereon, and united to an information 65 or data-bearing portion by two backing wings. The two backing wings, in some cases, are bent in opposite directions from the plane of the legs, and are connected to the data or information-bearing portion 70 along the longitudinal edges thereof, the construction being such that when the legs of the label are inserted between the cloth or fabric, and one surface of the holder or board, the data or information-bearing portion of the label may cover and lie close and snug against the end of the holder and also overlie part of the wound cloth or fabric. The extent of the data or information-bearing 75 portion of the label is altogether independent of the thickness of the board or holder, so that by varying the extent of the backing wings, the information-bearing portion of the label may be made sufficiently 80 large to receive any desired data or information.

To facilitate the insertion of the two legs together at one surface of the holder, one of the legs is made longer than the other, the longer leg being preferably the one 90 that comes next to the cloth or fabric when the label is in place, so that it acts as a protector or cover for the shorter leg as the label is placed in position. The backing wings which connect the legs with the information-bearing portion are of different extent or length between the respective legs and the longitudinal edges of the information-bearing portion, with the result that the longer backing wing covers or overlies 100 the end of the holder, but is free and unconnected thereto, so that in cases where a tag is to be attached to the holder or board between its side edges, as is sometimes desired, the attaching string or other flexible 105 tag connector may pass between the end of the cloth or fabric holder and the free overlying backing wing.

The label is preferably, though not necessarily formed of a cardboard or heavy paper which offers advantages in that the flexible material of the label may be readily folded 5 along the lines of bend which connect the legs and their respective backing wings, as well as the backing wings with the information-bearing portion of the label.

Novel features of the present invention 10 will be made clear from the following description and accompanying drawings, wherein:—

Figure 1 is a perspective view, some of 15 the cloth or fabric being broken away, and showing the label of the present invention being applied;

Fig. 2 is a longitudinal section, in perspective, showing the label with two legs being inserted between the one surface of 20 the holder or board and the adjacent fabric or cloth;

Fig. 3 is a longitudinal section through 25 one end portion of the wound cloth or fabric, showing the label fully in place and a tag attached to the board or holder; and

Fig. 4 is a plan view of a blank from 30 which the label is formed.

The board or holder 1 on which the cloth or fabric is wound or rolled, may be of 35 usual construction. In the present instance is it typified as a flat and substantially rectangular holder on which cloth or fabric 2 is wound layer after layer. There is nothing peculiar in the holder or board, 40 or in the way of rolling or winding the cloth or fabric thereon.

The label may be made of sheet material 45 which, for convenience, may be cut into blanks 3, such as shown by Fig. 4, for instance. In the present instance the sheet material is typified as light cardboard or heavy paper, and the blank 3 is formed with an oblong or pointed portion 4 at one side of an information-bearing portion 5, and a somewhat similar but shorter oblong portion 6 at the opposite side of the information-bearing portion. The two portions 4 and 6 constitute the legs of the label, the longer one 4 of which overlies the shorter leg 6, 50 and serves as a guide or protector for the shorter leg when the two legs are inserted between the cloth or fabric roll 2 and the surface of the board or holder 1.

The blank 3 may be appropriately scored 55 along the lines 7, 8, 9 and 10, such scores being spaced apart a distance determined by the size or dimension desired for the information-bearing portion of the label and the extent or relative sizes of the two backing wings which connect the legs with the information-bearing portion.

The longer leg 4 in the present instance is bent along the line 10 to provide an upwardly-extending portion 11 which constitutes the backing wing connecting the leg

4 with the information-bearing portion of the label. At the line 9 the material of the blank is again bent or turned and then carried downwardly as shown in Fig. 3, to constitute the information-bearing portion 12 70 of the label. Along the lower longitudinal edge of the information-bearing portion 12 the material of the label is turned along the line 8 and then carried upwardly to constitute the lower backing wing 13 which terminates at the fold line 7 where the lower backing wing joins the shorter leg 6 of the label.

From the construction as thus far described, it will be clear that the area of the 80 information-bearing portion 12 of the label may be varied and in some cases as shown by Fig. 3, it may be sufficiently large to cover not only the end portion of the board or holder 1, but also the edge portions of 85 the wound or rolled fabric 2. The extent of the information-bearing portion will be dependent upon the extent or size of the respective backing wings 11 and 13.

Since the label is unattached to the cloth 90 package by any positive connection therewith, it may be desirable to form the legs 4 and 6 of sufficient size to enable the label to be held frictionally and yet securely between the surface of the board or holder 95 and adjacent surface of the cloth or fabric wound thereon.

By reason of the fact that both legs 4 and 6 of the label enter between the same surface of the board or holder and the cloth 100 wound thereon, the backing wings 11 and 13 are of unequal extent. In the present instance the backing wing 11 is connected to the longer leg 4, while the longer backing wing 13 is connected to the shorter leg 6, 105 so that when the label is in place as indicated in Fig. 3, the backing wing will support the information-bearing portion of the label symmetrically and snugly against and with reference to the end of the cloth 110 or fabric package.

It is sometimes desirable to attach a tag 115 to the holder or board, such attachment being usually secured through the medium of a string or other flexible connection. In the present instance the holder or board 1 is shown as provided with an opening 14 substantially midway between the side edges of the board or holder, or substantially central thereof. The tag 15 is provided with a string or flexible connection 16 which, by reason of the label construction as hereinbefore described, is passed between the backing wing portion 13 of the label, then along the surfaces of the board or holder 1, through the opening 14 so that the tag may hang centrally from the end of the wound cloth package.

What is claimed is:—

A label for cloth wound upon a holder, 130

comprising in its construction a flat card board portion adapted to be inserted between one surface of the holder and the adjacent cloth wound upon the holder, and

5 an exposed label bearing portion also formed of card board and flexibly connected to the flat card board portion back of the label bearing surface longitudinally along a line of fold unequally distant from the two lon-

10 gitudinal edges of the label bearing portion that the narrower part of the label bearing

portion at one side of the flexible connection may cover exposed edges of the cloth at one side of the holder, and the wider part of the label bearing portion at the other side 15 of the flexible connection may cover the end of the holder and edges of the cloth at the other side of the holder.

In testimony whereof, I have signed my name to this specification.

STEPHEN C. LONERGAN.
